UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, A CORPORATION OF ILLINOIS.

SIGNAL SYSTEM.

Application filed January 23, 1922. Serial No. 531,065.

To all whom it may concern:

Be it known that I, DANIEL J. McCARTHY, a citizen of the United States, residing at Elgin, in the county of Kane and State of Illinois, have invented certain new and useful Improvements in Signal Systems, of which the following is a specification.

This invention relates to signal systems.

It is particularly applicable to poly-
10 chrome signals, such as used on railways,
and in other fields.

One of the objects of the invention is
to provide an improved signal.

Another object is to provide a signal
15 which may be manipulated readily to se-
lectively display a plurality of different
colored beams of light.

Another object is to provide a signal
wherein the selective display of different
20 colored lights may be effected by a simple
unidirectional movement of a series of re-
flectors.

Another object is to provide a signal
which may be inexpensively produced and
25 which will be efficient and reliable in opera-
tion.

Other objects and advantages will here-
inafter appear.

An embodiment of the invention is dia-
30 grammatically illustrated in the accom-
panying drawing, wherein—

Fig. 1 is a perspective of an arrangement
of prism reflectors which may be used for
the selective projection of beams of three
35 different colors.

Fig. 2 is a diagrammatic top plan of the
signal in position to project one color of
light, for example yellow.

Fig. 3 is a top plan of the signal in posi-
40 tion to project a different color of light,
for example green.

Fig. 4 is a side elevation of the project-
ing system and a schematic diagram of the
circuit connections, and

Fig. 5 is a side elevation of the signal
in position to project a third color of light,
for example red.

For a three-color system two right angled
prisms 1 and 2 may be used. The prisms
50 are placed one above the other and have
their diagonal faces in planes at right
angles to each other. Any suitable means,
such as ordinary ornamental window metal-
lic molding 3 may be used to secure the
55 prisms together in proper relation. Both

prisms are rigidly carried on a recipro-
cable plunger rod 4 secured to or forming
a part of a solenoid magnet armature 5.
The movement of armature 5 and rod 4
moves all of the prisms axially or in the
60 plane of their superposition. The axial
movement of armature 5, under the influence
of electromagnetic windings, selectively
positions the prisms, as will be hereinafter
described.

Prisms 1 and 2 are placed in a suitable
lamp casing (not shown) containing a lens
7 and three lamps 8, 9 and 10. Lamps 8,
9 and 10 are of different colors, such as
green, red and yellow respectively. Ordin-
70 ary lamps may be used if transparent
green, red and yellow plates or lenses 11
are interposed between the prisms and the
respective lamps. The lamps are all in the
same plane passing through the focal axis
75 of lens 7, the red lamp 9 being on the
axis and the green and yellow lamps 8
and 10 being on opposite sides thereof.

The prisms are arranged to be moved
axially so that either prism 1 or prism 2
80 may be interposed in front of all three
lamps, or both may be removed leaving an
unobstructed path between lamp 9 and
lens 7.

Armature 5 is controlled by two windings
85 12 and 13, which may be differentially
wound. Winding 12 is connected in series
with green lamp 8 and a source of current
14 through a suitable switch 15. Similarly
winding 13 is connected in series with yel-
90 low lamp 10 and battery 14 through a
switch 16. Red lamp 9 is in a circuit in-
cluding a switch 17 and source of current 14.

The closing of switch 16 completes the
circuit through yellow lamp 10 and wind-
95 ing 13. Winding 13 is energized and lamp
10 is illuminated. The energization of
winding 13 elevates armature 5 and plunger
rod 4 so that prism 1 is placed in front
100 of the three lamps, as shown in Fig. 2.
The yellow light from lamp 10 is refracted
by prism 1 and projected through lens 7
causing the signal to give a yellow indica-
tion. Green lamp 8 and red lamp 9 are not
105 illuminated because both of the circuits
therefor are open.

The closing of switch 15 completes the
circuit for winding 12 and green lamp 8.
The energization of winding 12 elevates
armature 5 and both prisms to the second
110

stage, bringing prism 2 in the plane of the lamps as shown in Figs. 3 and 4. Green lamp 8 is illuminated and prism 2 refracts the green light through lens 7, giving a green indication. Neither the red nor the yellow lamps are illuminated as their circuits remain open.

The closing of switch 17 closes the circuit for red lamp 9 but the circuit for both 10 windings remain open. Thus the prisms are not raised and the red lamp projects its light directly through lens 7 over the top of prism 1, giving a red indication.

Ordinarily a red indication is the danger 15 signal, and the usual practice in railway signalling is to have the red light visible normally so that if there should be a mistake in the closing of the circuits for the other signals or any other accidental or 20 inadvertent failure to give the proper indication the danger signal will be displayed. For example, the differential windings prevent the elevation of the prisms if the switches for both the green and yellow 25 lamps are closed together. This leaves the system in position to display the red or danger signal.

The lamps, windings and switches may 30 be of any suitable construction. The switches may be either manually or automatically controlled. Manual switches and relay switches of suitable types are well known in the art. Ordinarily the switches are so related that the contacts controlling the red 35 lamp are normally closed, to be open when either the contacts for the yellow or the green lamp are closed and to be closed or remain closed when both the contacts for the yellow and green lamps are simultaneously closed.

Any suitable means for deflecting the light beam may be used in place of the prisms and throughout the description and claims the word "reflector" is used in the 45 sense of including any suitable means which will serve to reflect or refract the beams of light.

Having described my invention what I 50 claim as new and desire to secure by Letters Patent, is:—

1. A signal system having a plurality of superposed reflectors arranged to project light from different directions, a plurality

of sources of light arranged about the reflectors, and means for causing relative 55 movement between the reflectors and the sources so that each reflector may be selectively caused to project the light from a corresponding source.

2. A signal system having a plurality of 60 sources of light, a reflector for each source, the reflectors being superposed, and means for causing relative movement between the reflectors and the sources so that any one reflector 65 may be brought into projecting relation to its corresponding source of light.

3. A signal system having a series of superposed reflectors movable in the plane of superposition, a source of light for each reflector, the sources being located in a common plane transverse to the direction of movement of the reflectors, and means for selectively moving the reflectors so as to bring any one into the plane of the sources of light to project the light from the corresponding source. 70 75

4. A signal system having a plurality of superposed reflectors, a source of light for each reflector, and electromagnetic means for selectively producing relative movement 80 between the reflectors and the sources to bring any one reflector into projecting relation to a corresponding source.

5. A signal system having a series of superposed reflectors, a source of light for each reflector, electromagnetic means including an armature for causing selective movement between the reflectors and the sources so as to bring any one reflector into projecting relation relative to a corresponding 85 source, and a plurality of windings comprising parts of the electromagnetic means for selectively controlling the armature. 90 95

6. A signal system having a plurality of superposed reflectors, a source of light for each reflector, electromagnetic means for causing movement between the reflectors and the sources so that any one reflector may be brought into projecting relation to a corresponding source, and a plurality of differentially related windings comprising parts of the electro-magnetic means. 100

In testimony whereof I hereunto subscribe my name.

DANIEL J. McCARTHY.
